DISPLAY RACK HAVING MOVABLE PARTS

Homer C. Douglas, Kansas City, Kans.

Application November 3, 1949, Serial No. 125,333

3 Claims. (Cl. 211—1.6)

1

This invention relates to a display rack of the kind having a rotatable plate preferably disposed at an angle with respect to the horizontal and provided with article supports thereon so formed and interconnected with actuating means as to maintain the supports in a predetermined position with respect to the horizontal and the vertical as the plate rotates.

Another important object of the present invention is to provide a display rack having a pair of rotatable plates provided with offset axes, there being cranks pivotally interconnecting the plates whereby rotation of one of the plates imparts like movement to the other plate and the cranks each extending beyond the outermost face of plates to present an article support.

A further object of the present invention is to provide a display rack wherein all of the aforesaid cranks are provided with stabilizing means in the nature of wings integral therewith and interposed between the plates for free sliding movement with respect thereto.

A further object of the present invention is to provide novel lubricating means for the cranks of the display device in the nature of absorptive pads supported by the cranks themselves between the plates.

A still further object of the present invention is to provide a display device having a pair of plates as aforesaid wherein one of the plates has a relatively large, centrally disposed, circular opening for clearing a drive shaft for the other plate, said opening circumscribing a plurality of supporting rollers for the plate having the opening therein.

Other objects including particular details of construction will be made clear or become apparent as the following specification progresses, reference being had to the accompanying drawing, wherein:

Fig. 1 is a front elevational view of a display rack having movable parts made in accordance with my present invention, parts being broken away to reveal details of construction; and

Fig. 2 is a substantially central, vertical, cross-sectional view taken on line II—II of Fig. 1.

A hollow housing, broadly designated by the numeral 10, may be provided if desired, with a suitable door or removable wall (not shown) to render the interior thereof readily accessible. Housing 10 is provided with a flat, forwardmost wall 12 that is disposed at an angle with respect to the vertical as clearly shown in Fig. 2 of the drawing.

A down-turned flange 14 extending from front

wall 12, serves as a supporting leg for the housing 10 and is provided with a U-shaped resilient foot 16. Similar feet are provided for the housing 10 near the rearmost wall thereof, one only being shown in Fig. 2 of the drawing and designated by the numeral 18.

An electric motor or other suitable prime mover 20 is mounted within the housing 10 through use of a bracket 22, said motor having a horizontally disposed drive shaft 24 which in turn is provided with a relatively small pulley 26. A larger pulley 28 mounted on a shaft 30 above the motor 20 within the housing 10 receive a continuous belt 32 and is also trained about the pulley 26 of motor 20.

Shaft 30 has a worm 34 thereon that is in mesh with a gear 36 and in turn disposed within a tubular member 38. Member 38 rigidly secured within the housing 10, serves not only as a support for the shaft 30 but for a shaft 40 disposed at an angle and perpendicular to the wall 12 through which it extends.

Gear 36 is rigidly secured to the shaft 40 as is a preferably circular plate 42 exteriorly of the housing 10.

Plate 42 is provided with an annular flange 44 that extends toward the wall 12 of housing 10 and is mounted on the shaft 40 through the medium of a nut 46 rigid to the innermost face of plate 42 and threaded on the proximal outermost end of shaft 40. Plate 42 is substantially parallel in width and spaced from the outermost face of wall 12 as is a second circular plate 48 having a diameter appreciably less than the diameter of plate 42. Plate 48 is within the flange 44 of plate 42 and is provided with a relatively large circular and centrally disposed opening 50. Opening 50 clears the shaft 40 and is eccentrically disposed with respect thereto.

A plurality of rollers 52 is mounted for free rotation on the outermost face of wall 12 in engagement with the periphery of opening 50. Rollers 52 are each provided with an external flange 54 that underlies the plate 48 and serves as a support therefor.

A plurality of cranks broadly designated by the numeral 56 interconnect the plates 42 and 48 and serve primarily to impart rotative movement to the latter. Cranks 56 are identical and each include an arm 58 that underlies the plate 42; a finger 60 on one end of the arm 58 and perpendicular thereto; a second finger 62; a horizontal branch 64; and a vertical leg 66. The finger 60 is rotatably mounted within an opening 68 in the plate 48 adjacent its peripheral edge,

whereas the finger 60 projecting oppositely with respect to finger 62 passes through a bushing 70 mounted within the plate 42 in spaced relationship with the peripheral edge of the latter. The branch 64 extends outwardly from the bushing 70 and from the outermost face of plate 42, whereas the leg 66 extends upwardly from the outermost end of the branch 64 and is integral therewith.

Each arm 58 has a pair of laterally extending loops or wings 72 formed integrally therewith. The wings 72 are oppositely disposed within a common plane and interposed between the proximal faces of plates 42 and 48.

Each finger 60 is provided with a small disc-like pad of absorptive material 74 that is threaded thereon and interposed between the wings 72 and the proximal face of plate 48.

Shaft 40 is hollow and an elongated rod 76 extends therethrough, rod 76 being held against rotation by a collar 78 affixed in any suitable manner to the member 38 and having a setscrew 80 that bears against rod 76. Rod 76 terminates at its opposite end beyond the outermost face of plate 42 in a horizontal branch 82 and a vertical leg 84.

In operation, as soon as the motor 20 is energized, shaft 40 will be caused to rotate through shaft 24, pulley 26, belt 32, pulley 28, shaft 30, worm 34 and gear 36. Upon rotation of the shaft 40, plate 42 will accordingly rotate and impart similar rotative movement to the plate 48. The cranks 56 serve to so actuate plate 48 because of the pivotal connection between fingers 62 and bushing 70, as well as between the fingers 60 and the openings 68 in plate 48. Saturating of the pads 74 with a suitable lubricant serves to impede wear between fingers 60 and their corresponding openings 68. As the plate 48 rotates on the rollers 52 and as the plate 42 rotates simultaneously therewith on offset axes, the branches 64 will always remain horizontal and similarly, the legs 66 will always maintain a vertical position. Obviously, the branch 82 and the leg 84 will maintain the position illustrated because of the fact that the rod 76 is immovable. Because of the provision of the wings 72 within the arm 58 of cranks 56, all of such cranks 56 will be stabilized and held in the position shown since wings 72 cannot tip when slidably interposed between the plates 42 and 48 as shown.

It is furthermore apparent that precision of construction is not necessary because of the fact that the flexible wing elements 72 will yield or spread sufficiently during tendencies of binding and permit continued rotation of the plates 42 and 48 with a minimum amount of power emanating from prime mover 20.

While the cranks 56 have been shown as terminating in a horizontal branch 64 and a vertical leg 66, it is quite apparent that such construction may be varied to suit the desires of the user and to adapt the same to carry differing types of articles. Relatively small articles of merchandise may well be hung or otherwise affixed to the branches 64 and/or the legs 66 or other shelving

or supporting means provided in lieu of branches 64 and legs 66 or in conjunction therewith.

The angularly disposed, outermost plate 42 completely hides from view the plate 48, all of its associated parts and the housing 10.

The display device is not only attractive but produces a pleasing and interesting effect that is sure to attract attention and aid in the selling and advertising of various types of articles of merchandise. More particularly, the entire device is simple, inexpensive, requires little power to operate and can be used for extremely long periods of time without necessity of maintenance or repair. Accordingly, while the display apparatus is capable of many changes and modifications, it is desired to be limited only by the spirit of this invention as defined by the scope of the appended claims.

Having thus described the invention, what is claimed as new and desired to be secured by Letters Patent is:

1. In a display apparatus, a first and a second plate, said plates being superimposed and mounted for rotation on offset axes; a crank pivotally interconnecting the plates for imparting rotative movement to said second plate as the first plate is rotated; and stabilizing means for the crank disposed between the plates and including a pair of oppositely extending wings on the crank.
2. In a display apparatus, a first and a second plate, said plates being superimposed and mounted for rotation on offset axes; a crank pivotally interconnecting the plates for imparting rotative movement to said second plate as the first plate is rotated; and at least one wing integral with the crank and disposed between the plates in parallelism therewith for stabilizing the crank.
3. In a display apparatus, a first and a second plate, said plates being superimposed and mounted for rotation on offset axes; a crank pivotally interconnecting the plates for imparting rotative movement to said second plate as the first plate is rotated; and at least one flexible member forming a part of the crank and extending laterally therefrom between the pivotal points on the plates for stabilizing the crank.

HOMER C. DOUGLAS.
